UNITED STATES PATENT OFFICE.

DOSIER H. MOSTELLER, OF OAK PARK, ILLINOIS.

STRAW-DISPENSER.

1,267,579.

Specification of Letters Patent. Patented May 28, 1918.

Application filed April 2, 1915, Serial No. 18,778. Renewed October 22, 1917. Serial No. 197,993.

To all whom it may concern:

Be it known that I, DOSIER H. MOSTELLER, a citizen of the United States, residing at Oak Park, Cook county, Illinois, have invented certain new and useful Improvements in Straw-Dispensers, of which the following is a specification.

The present invention has reference to certain improvements in straw dispensers of that type in which the straws are carried in a receptacle from which they may be removed one at a time through the upper portion thereof. The main objects of the invention are to facilitate and improve the delivery of the straws to the discharge opening whence they may be removed by the customer. Also to so construct the lid and opening of the dispenser that the straws may be more easily grasped individually and without confusion or interference. Another object is to so construct the dispenser that the last straw may be reached as readily as the first one to be removed, thus making the dispenser of uniform operation and usability.

Other objects and uses will appear from a detailed description of the invention which consists in the features of construction and combinations of parts hereinafter described and claimed.

Referring to the drawings:

Figure 1 shows a side elevation of the straw dispenser, the lower portion of the same being broken into sections so as to show the form of the bottom portion;

Fig. 2 is a perspective view of the top portion of the dispenser shown in Fig. 1, the lid being raised for the delivery of a straw; and

Fig. 3 is a section through the top portion of Fig. 1 showing the manner in which the straws lay toward the front or delivery portion.

Referring to the figures, the body portion 4 is shown as having its upper end tilted forward with respect to its base end 5 so that the straws will normally lie toward the front edge 6. In this way the straws will normally be thrown toward said front edge for delivery thereto.

The top front portion has its edges 7 and 8 slanted down commencing substantially at the central line of the dispenser, and the finger openings 9 and 10 are provided at the extreme front portions of the edges 7 and 8. The upper ends of the straws are thus natu-

rally thrown toward the finger openings 9 and 10.

When the dispenser is first filled the straws will lie in a large body substantially parallel to each other and will be to the front portion of the casing. The first straw to be removed will be that one which occupies the extreme front position. As the straws are removed, one at a time, their upper ends will tilt forward more and more so that the front straw will always lie with its upper end between the finger openings 9 and 10. If the bottom of the case were to be perfectly flat there would be no tendency for the lower ends of the straws to slide toward the front, and consequently as the upper ends of the rear straws approached nearer and nearer to the finger openings 9 and 10, said straws would lie at a greater and greater angle from the vertical, and the upper end of each succeeding straw would stand lower than the straws which preceded it. The result would be that it would either be necessary to make the finger openings 9 and 10 undesirably deep or else it would be very difficult to secure a firm hold on the latter straws.

In order to meet the foregoing objection I have peculiarly formed the bottom of the case. In the particular construction shown in Fig. 1 the bottom 11 is curved upward from front to back substantially on the arc of a circle of which the finger openings 9 and 10 are the center. It thus follows that when practically all of the straws have been removed the upper ends of the last straws will stand at as great an elevation adjacent to the finger openings 9 and 10 as the elevation at which the first straws stood. In addition to this fact there will be a natural tendency for the lower ends of the straws to slide or work forward in the casing on account of the peculiar form of the bottom. While I have shown the bottom as being drawn substantially on the arc of a circle, it will, nevertheless, be understood that substantially the same results would be secured if the bottom were to be made flat with its rear portion at a greater elevation than its front portion.

On the top of the casing is mounted a suitable cover. The cover illustrated comprises the rear portion 12 having the flange 13 encircling the upper edge of the rear portion of the case, and the lid 14 which is pivoted to the rear portion 12 of the cover. The lid 14 has the lips 15 and 16

which extend in position to close over the finger openings 9 and 10, there being a lug 17 on the lower edge of each of said lips. The lips are separated a sufficient distance 5 to leave a slot or opening 18 between them, through which slot or opening the straws may be removed.

With this arrangement the customer slides his thumb and finger upward along the front 10 edge of the case until the thumb and finger come into contact with the lugs 17. Thereupon the lid 14 is raised, and the thumb and finger pass through the openings 9 and 10 to grasp the forward straw. As the lifting operation is continued this straw is removed, sliding out through the slot 18 between the lips 15 and 16. With this arrangement of parts it is a very simple matter for the customer to withdraw the forward straw at each operation.

In order to assist the delivery of the straws to the front of the casing a wire 19 may have its upper ends 20 pivoted to the casing so that its central portion will rest 25 against the upper ends of the straws to throw them forward.

While I have herein shown and described only a single embodiment of my invention, still it will be understood that I am in no 30 wise restricted to the said embodiment except as I am restricted in the claims.

I claim:

1. A device for dispensing straws or the like, comprising a hollow body portion of 35 cylindrical form, a base member whereon said body portion is mounted, said base member being so formed that the body portion tilts forward when the base stands on a horizontal surface, the forward portion 40 of said body having its walls drawn together to provide an angular space between them, there being a pair of notches in the upper adjacent portions of said surfaces, the bottom of the receptacle being formed substantially on the arc of a circle drawn about 45 said notches as a center, and a lid pivotally mounted on the upper portion of the recep-

tacle, said lid being provided with a pair of downwardly depending ears adapted to lay over and close the aforementioned notches when the lid is lowered, lugs on the lower ends of said ears, and there being a notched opening between the ears.

2. A device for dispensing straws or the like, comprising a hollow body portion of cylindrical formation, a base member whereon said body portion is mounted, said body portion being so positioned on the base member that when the base member stands on a horizontal surface, the body portion tilts forwardly, the forward portion of the interior of the body being angular for the purpose of delivering straws or the like one at a time to the extreme forward position, there being a pair of notches in the upper portion 60 of the body disposed at opposite sides to the extreme forward position of a straw, and a cover pivotally mounted on the upper portion of the straw dispenser, said cover having a pair of downwardly depending ears 65 adapted to cover over the aforementioned notches when the cover is lowered, and there being a notched opening between said ears.

3. A device for dispensing straws or the like, comprising a hollow body portion, a 70 base member whereon said body portion is mounted, said base member being so formed that when it stands on a horizontal surface, the body portion tilts forwardly, the forward portion of the body drawing together 75 in such a manner that articles contained in bulk within the body feed one at a time to the extreme forwardmost position, there being a pair of notches in the upper portion of the body disposed at opposite sides to the 80 extreme forwardmost position, and the bottom of the body being formed substantially on the arc of a circle formed on said notches as a center.
